UNITED STATES PATENT OFFICE.

HARRY A. FREDERICK, OF NEW ROCHELLE, NEW YORK.

CALENDAR DEVICE.

Application filed July 26, 1928. Serial No. 295,404.

This invention relates to a calendar device. It is aimed to provide an exceedingly compact construction which will constitute a novelty in addition to its handiness or usefulness and may be used in relatively small form, as on the ends of writing instruments either as a 5 attachment or an initial part thereof, as a watch charm, as a knob or handle on a clock and in various other relations.

10 The invention consists of various coacting parts which will show the year, the month, the day and the number of days in the month.

The more specific objects and advantages will become apparent or be pointed out in the 15 description following taken in connection with accompanying drawings illustrating an operative embodiment.

In said drawings:—

Figure 1 is a side elevation showing the invention applied as an attachment to a fountain pen;

Figure 2 is an enlarged side elevation of the calendar device;

Figure 3 is a central vertical section taken 25 through the calendar device on the same scale as Figure 2;

Figure 4 is a cross sectional view taken on the line 4—4 of Figure 3;

Figure 5 is a cross sectional view taken on 30 the line 5—5 of Figure 3;

Figure 6 is a cross sectional view taken on the line 6—6 of Figure 3;

Figure 7 is a cross sectional view taken on 35 the line 7—7 of Figure 3, and

Figure 8 is a cross sectional view taken on the line 8—8 of Figure 2.

Referring specifically to the drawings, the calendar device constituting my invention is generally designated A. By way of example, such device is shown used as an attachment on a fountain pen conventionally illustrated at B in Figure 1. The device is capable of general use as previously mentioned and hence no limitation as to use on a fountain 40 pen or writing instrument is to be inferred.

The device per se has a central body 10 of cylindrical form. This body may have a reduced lower end 11 whereby it may be fastened by upsetting at 12 to an attaching head 13 having interior screw threads 14. The threads 14 may engage those usually found at the top of the barrel of the fountain pen B and normally engaged by a cap thereon, which cap is discarded to accommodate the 50 use of the calendar device. It is to be noted that the cap 13 need not be a separate piece

from the body 10 and further need not be detachable from the fountain pen but that the body 10 may be provided on the barrel of the fountain pen in any approved manner when 60 built into the fountain pen or writing instrument initially.

Adjacent the top, body 10 has integral with it, a disk 15.

Surrounding the body 10 below the disk 15 65 is a sleeve 16 which is capable of sliding movement longitudinally of the body 10 and of rotation thereon. Said sleeve 16 normally however is in uppermost position in contact with the under surface of disk 15 through the 70 agency of an expansive spring 17 surrounding body 10, located in a recess 18 in the sleeve and abutting such sleeve and the attaching head 13.

On the periphery of the disk 15 is an indication for each day of the week as at 19 and coacting therewith, the periphery of the sleeve 16 has seven vertical columns 20 of figures indicating the days of the month. The upper row has figures running from left to right 75 from one to seven, the next row left to right from eight to fourteen, the next row to the right from fifteen to twenty-one, the next row to the right from twenty-two to twenty-eight and the next row to the right from twenty-nine to thirty-one, it being observed 80 that the figures one, eight, fifteen, twenty-two and twenty-nine occur in the same vertical column. As a result of this construction, turning of the sleeve 16 enables the 85 column containing one to be brought in line with the appropriate day at the start in a given month in line with the day indications 19.

Sleeve 16 is circumferentially grooved as at 95 21 to accommodate a rotatable resilient clasp band 22, its frictional contact with the sleeve serving to hold it in different adjusted positions. A vertical enlargement 23 constitutes a shield to conceal the numerals twenty-nine, 100 thirty and thirty-one, or any of them, according to the number of days in a given month. An outward projection 24 is struck in the band 22 for engagement by the finger in adjusting it relatively to the sleeve. 105

Corresponding with each of the seven day indications 19, the under surface of disk 15 has seven recesses or notches 25 provided therein and they are selectively engageable according to the registration desired between 110 26 the indications 19 and the columns 20, by a lug provided on the upper surface of the

sleeve 16. The slidable mounting of the sleeve against the tension of the spring 17 enables engagement and disengagement of the lug 26 and recesses 25.

5 The upper surface of disk 15 has a depression or is countersunk as at 27 and a rivet or screw 28 is detachably or non-detachably secured centrally of the body 10 as preferred. Rotatably mounted on the shank 29 of said element 28 are plates 30 and 31. Said plates are movable independently and to facilitate their movement, lugs 32 and 33 are provided thereon, respectively. The upper surface of the disk 15 or base of its depression has segmental delineations for each month of the year 34, as best shown in Figure 6. The plate 30 moves over the delineations 34 and has a segmental cut away portion, slot or window at 35 of a size to expose one of the delineations 34 at a time. Thus as shown in Figure 5, January alone is exposed and the other months are concealed. The plate 31 operates above and over the plate 30 and it has a window, slot or cut away portion at 36 through which delineations 37 of the plate 30, may be seen or brought into registry one at a time. Such delineations 37 may run consecutively from twenty-eight to thirty-six or higher if preferred. Coaction with such delineations, is the numeral 19 as indicated particularly in Figure 4. Thus with the window 36 registering with indication 32 on plate 37, it will be seen that the year will be read as 1932 and since the month "Jan." is exposed, 35 it will be seen that both the month and the year are given. The coacting delineations 19 and 20 of the disk and cylinder or sleeve previously traced completes the calendar giving the week and the days.

40 Various changes may be resorted to provided they fall within the spirit and scope of the appended claims defining the invention.

I claim as my invention:—

1. A calendar device of the class described 45 having a body provided with a disk, a sleeve rotatable on said body and slidably relatively to the disk, means maintaining the disk and sleeve in operative relation, one of the parts having a plurality of recesses, the other hav-

ing a lug to selectively engage the recesses, 50 spring means engaging the sleeve and adapted to hold the lug in engagement with the recesses, and coacting calendar indications on the disk and sleeve adapted to be brought in registration and so held by said lug and recesses.

2. A calendar device of the class described having a body provided with a disk, a sleeve slidable and rotatable on said body, means maintaining the disk and body in operative 60 relation, one of the parts having a plurality of recesses, the other having a lug to selectively engage the recesses, and coacting calendar indications on the disk and sleeve adapted to be brought in registration and so 65 held by said lug and recesses, said body having indications for the months thereon, a plate movable thereover having year indications thereon, a window to expose said month indications, and a plate movable above the first mentioned plate having a window thereon to expose said year numbers, and a year number on the last mentioned plate to coact with the year numbers of the first mentioned plate.

3. A device of the class described having an attaching head, a body extending therefrom provided with a disk, said disk having recesses in its under surface, a sleeve slidable and rotatable on said body and having a projection to selectively engage said recesses, 80 an expansive spring surrounding the body and engaging said sleeve and said attaching head to maintain the lug and recesses in engagement, coacting calendar indications on said disk and sleeve, to show the arrangement 85 of the days in a given month, the disk having a recess and provided therein with month indications, a plate in said recess movable over said indications and having a window to expose the same one at a time, said plate 90 having year numerals thereon, a plate movable over the first mentioned plate having a window to expose said year numerals one at a time, and a year numeral on the last mentioned plate to coact with said year numerals.

95 In testimony whereof I affix my signature.

HARRY A. FREDERICK.
